UNITED STATES PATENT OFFICE.

GEORGE T. MCLEOD, OF BOSTON, MASSACHUSETTS, ASSIGNOR TO THOMAS G. PLANT COMPANY, OF BOSTON, MASSACHUSETTS, A CORPORATION OF MASSACHUSETTS.

BOOT OR SHOE AND PROCESS OF MAKING.

Application filed January 11, 1923. Serial No. 611,943.

To all whom it may concern:

Be it known that I, GEORGE T. MCLEOD, a citizen of the United States, and resident of Boston, in the county of Suffolk and State of Massachusetts, have invented an Improvement in Boots or Shoes and Processes of Making, of which the following description, in connection with the accompanying drawings, is a specification, like 10 letters on the drawings representing like parts.

In my present invention I have devised a novel and extremely flexible method of making boots or shoes, following substantially the McKay or through-and-through stitching method of uniting insole, outsole, and upper, while having a portion of the shoe at the shank free or "released" from such stitching through the insole, and hence 20 producing a flexible McKay shoe.

It is important to make certain grades of footwear so that they will possess great flexibility, but the McKay shoe and methods of manufacture tends, ordinarily, 25 to produce a rigid or stiff and non-flexible shoe. Heretofore various efforts have been made to provide flexibility, particularly the shank portion, but these prior methods have necessitated the making of the shoe by 30 means of difficult operations involving skilled hand work, and special machines. My present invention aims to produce an extremely flexible shoe by the simple and inexpensive McKay process, and by utilizing 35 a novel construction and method of McKay shoe manufacture which will follow substantially all the present day operations utilizing standard machines, and the present labor rates on piece work, and the like. 40 This advantage is of considerable importance, as it is possible to make the shoe here- 45 in illustrated without disorganizing present shoe factory methods, and yet to produce an efficient, extremely flexible shoe by the well-known and economical McKay shoe methods.

In the prior U. S patents of W. J. Mac-Farland No. 1,101,747 and 1,101,748, and in the patent application of George T. McLeod, Ser. No. 404,314, an important type 50 of extremely flexible or so-called "released shank shoe" construction, is shown as applied to welt footwear and the present invention aims to provide for McKay footwear and equally desirable, advantageous

and flexible shoe construction of the "released shank type." Further advantages, important features and details of construction will be hereinafter more fully pointed out and claimed. 60

Referring to the drawings illustrating a preferred embodiment of my novel shoe made by my novel process.

Fig. 1 is a bottom plan view of the invention after the shoe is McKay lasted; 65

Fig. 2 is a cross-sectional view showing the insole on the inner or foot-contacting surface;

Fig. 3 is a cross-sectional view of the shank portion, on the line 3-3 of Fig. 1; 70

Fig. 4 is a similar cross-sectional view of the completed shoe.

In carrying out the present process, I 75 form the insole 1 with a reduced or cut-away portion along the shank on the inside of the arch, viz., on the right edge of the left shoe and correspondingly on the left side of the right shoe, this cut-away portion being substantially as indicated in 80 Fig. 2 from adjacent the heel 2 up to the forepart at 3 in order to clear the through and through stitching 5, thus giving a curved part or edge 4 of the insole which will be entirely free of the through and 85 through stitching, as best shown in Figs. 2 and 4. The insole 1 is then applied to the last bottom and the upper materials 6 assembled on the last, and the shoe is lasted in the usual McKay shoe construction, the 90 lasting tacks 7 being driven in and clinched on the iron bottom of the last 10, Fig. 1. These lasting tacks, however, are omitted from the edge of the heel breast to the adjacent ball or part of the forepart, sub- 95 substantially on the points where the insole is cut away from 2 around the curve 4 to the point 3 as shown in Fig. 1. The upper along this portion may be, and preferably is, first stitched to a wide strip or sheet of 100 material 12 by stitching 13, before the upper is assembled on the last, although it is possible to stitch this piece 13 after the upper is first assembled, if desired. This strip or member 12 is of suitable width to 105 extend across the last and also has a projecting marginal portion 15 extending beyond the attaching stitching 13. The strip 12 is then pulled over, by hand or otherwise, and attached by lasting tacks to the oppo- 110

105
110

site edge of the shoe, as indicated in Fig. 1 at 21, 21. These lasting tacks 21 can be driven through into the insole and clinched therein also, although I prefer to use short 6 tacks which may be buried in the thickness of the upper materials and the insole, this being for temporary use only, the through and through stitching afterwards catching this edge portion of the strip 12.

10 With the shoe thus lasted, and the insole from approximately the heel portion at 2 up to the forepart 3 on the inside or shank part free of lasting tacks and thus released from both the upper and the insole, 15 this part of the insole will be free to bend or flex during the subsequent use of the shoe.

With the shoe thus made, I then apply the outsole, put same through the levelling or sole-laying process, and then withdraw

20 the last and insert the McKay or through and through stitching 5. The shoe thus completed has its shank portion entirely free from the insole, along the inner or arch side as above noted, and with the upper 25 fitting snugly around this part of the arch and permanently attached to the outsole through the free or released insole portion and also permanently attached through the strip 12 to the insole and outsole along the

30 opposite edge portion. Thus an extremely flexible shoe construction is provided in an otherwise McKay shoe structure, and by means of adding the strip or extension 12. This member 12 may be of leather, canvas or 35 other suitable textile material if desired, or of course could be an extension of the upper materials themselves, but the preferred method of attaching same is as described above. With the outsole applied the outer

40 edge 15 of this strip can be cemented and trimmed with the trimming of the outsole, or it can be cut closely to the attaching seam 13. I believe that my method of thus manufacturing a "released shank shoe" of 45 the McKay type and by McKay shoe methods, as well as the resulting flexible shoe structure produced thereby is a novelty in the art and therefore I wish to claim both the process and the resulting shoe broadly.

50 My invention is further described and defined in the form of claims as follows:

1. The improved method of making a boot

or shoe, which consists in providing an insole with a narrowed portion along the inner shank part, assembling the insole thus 55 prepared and an upper on a last, said upper having an extension to the upper materials from the shank portion adjacent the narrowed insole and adapted to extend to the opposite edge portion of the insole at the 60 shank, lasting the upper, and securing the lasted upper to the insole, excepting at the narrowed insole shank portion, lasting and securing the extension to the upper on the opposite edge of said narrowed shank portion, applying an outsole and uniting the insole, outsole and upper materials by 65 through and through stitching, excepting along the narrowed shank portion on the inside arch of the shoe. 70

2. The improved method of making a McKay shoe having the insole free of McKay stitching, from adjacent the heel breast to the forepart on the inside shank portion, consisting in first preparing an insole with 75 the edge adjacent the inside arch of the shoe cut away from the heel to the forepart to form the insole of less width than the line of McKay stitching to be inserted in the shoe, providing the upper with means 80 to hold the inside arch portion extending across the insole and attached to the edge of the insole opposite the cut away portion of the insole, lasting the shoe, applying the outsole, and securing the insole, upper materials and outsole by through and through stitching, said stitching running off the insole from the forepart to the heel breast along said cut away edge, and uniting only 85 the upper materials to the outsole. 90

3. An improved boot or shoe, having an insole with the edge adjacent the inner arch portion of the shank narrowed, the upper materials at the corresponding shank portion having an extension adapted to secure this 95 part of the upper to the opposite edge of the insole, said upper and insole being attached excepting at the narrowed insole portion, and the upper, insole and outsole being secured by through and through stitching, 100 excepting at said narrowed insole portion.

In testimony whereof, I have signed my name to this specification.

GEORGE T. McLEOD.
